thothiazoles such as α -naphthothiazole, β -naphthothiazole, β,β -naphthothiazole, 8-methoxy - β - naphthothiazole, 5-ethoxy- β -naphthothiazole, 7-methoxy- α -naphthothiazole, 8-methoxy- α -naphthothiazole, 5 - hydroxy- β -naphthothiazole, 7-hydroxy- α -naphthothiazole and 5-ethyl- β -naphthothiazole; oxazoles such as oxazole, 4-methyloxazole, 5-methyloxazole, 5 - phenyloxazole, 4 - (p-hydroxyphenyl)oxazole, 4,5-diphenyloxazole, 4-ethyloxazole, 4,5-dimethyloxazole, 4-phenyloxazole, and 5-(m-hydroxyphenyl)oxazole; benzoxazoles such as benzoxazole, 5-chlorobenzoxazole, 5-methylbenzoxazole, 5-phenylbenzoxazole, 6-methylbenzoxazole, 6-nitrobenzoxazole, 5,6-dimethylbenzoxazole, 4,6-dimethylbenzoxazole, 5-methoxybenzoxazole, 5 - ethoxybenzoxazole, 6 - chlorobenzoxazole, 6-methoxybenzoxazole, 5-hydroxybenzoxazole and 6-hydroxybenzoxazole; naphthoxazoles such as α -naphthoxazole, β,β -naphthoxazole, β -naphthoxazole and 6-hydroxy- β -naphthoxazole; selenazoles such as selenazole, 4-methylselenazole, 4-phenylselenazole and 4-(p-hydroxyphenyl)selenazole; benzoselenazoles such as benzoselenazole; 5-chlorobenzoselenazole, 5-methoxybenzoselenazole, 5-hydroxybenzoselenazole and tetrahydroxybenzoselenazole; naphthoselenazoles such as α -naphthoselenazole, β,β -naphthoselenazole, β -naphthoselenazole and 7-hydroxy- β -naphthoselenazole; thiazolines such as thiazoline, 4-methylthiazoline, and 4-(p-hydroxyphenyl)thiazoline; 2-quinolines such as quinoline, 3-methylquinoline, 5-methylquinoline, 7-methylquinoline, 8-methylquinoline, 6-chloroquinoline, 8-chloroquinoline, 8-fluoroquinoline, 6-methoxyquinoline, 6-ethoxyquinoline, 6-hydroxyquinoline, 7-hydroxyquinoline and 8-hydroxyquinoline; 4-quinolines such as quinoline, 5-methoxyquinoline, 6-methoxyquinoline, 7-methoxyquinoline, 8-methoxyquinoline, 6-methylquinoline, 7-chloroquinoline and 8-trifluoromethylquinoline; isoquinolines such as isoquinoline, 5-methyl-1-isoquinoline, 7-methyl-1-isoquinoline, 6-chloro-1-isoquinoline, 6-methoxy-1-isoquinoline and 8-methoxy-1-isoquinoline; 6 - chloro-3-isoquinoline, 6-methoxy-3-isoquinoline and 8-methoxy-3-isoquinone; 3,3-dialkylindolenines such as 3,3-dimethylindolenine, 5-hydroxy-3,3-dimethylindolenine, 3,3-dimethyl-6-chloroindolenine, 3,3,5 - trimethylindolenine and 3,3-dimethyl-5-nitroindolenine; 2-pyridines such as pyridine, 6-methylpyridine, 4,6-dimethylpyridine, 4-butylpyridine, 4-decylpyridine, 4-octadecylpyridine, 4,6-dibutylpyridine, 4-benzylpyridine, 4-phenylpyridine, 4-(p-hydroxyphenyl)pyridine, 4,6 - diphenylpyridine, 4,6 - dinaphthylpyridine, 4-chloropyridine, 4-bromopyridine, 4,6-dichloropyridine, 4-chloropyridine, 6-bromopyridine, 4-hydroxypyridine, 4-methoxypyridine, 4-ethoxypyridine, 6-methoxypyridine, 6-ethoxypyridine and 4,6-dimethoxypyridine; pyridines such as pyridine, 2-butylpyridine, 2-methylpyridine, 2-butylpyridine, 2-decylpyridine, 2-octadecylpyridine, 2,6-dibutylpyridine, 2-benzylpyridine, 2-phenylpyridine, 2-(p-hydroxyphenyl)pyridine, 2,6-diphenylpyridine, 2-chloropyridine, 2-bromopyridine, 2,6-dichloropyridine, 2-hydroxypyridine, 2-methoxy - pyridine, 2-ethoxypyridine and 2,6-dimethoxypyridine; imidazo-(4,5-b)-quinoxalines such as 1,3-diethylimidazo-(4,5-b)-quinoxaline, 1,3 - diethyl - 6 - nitro-imidazo-(4,5-b) - quinoxaline, 1,3 - diphenylimidazo - (4,5-b) - quinoxaline, 6-chloro - 1,3 - diphenylimidazo - (4,5-b) - quinoxaline, 1,3-diallylimidazo - (4,5-b) - quinoxaline and 1,3-dicyclohexylimidazo-(4,5-b)-quinoxaline; oxazoline and benzimidazoles such as benzimidazole, 5,6-dichlorobenzimidazole, 1-ethyl-5-nitrobenzimidazole and 1-ethyl-5,6-dichlorobenzimidazole.

The dimethinecyanine dyes used in the present invention can be synthesized, for example, by reacting aldehyde derivatives of indole compounds having a hydrogen atom, chlorine atom, lower alkyl group, carboxyl group or lower alkoxy carbonyl group in the 2-position with alkyl substituted quaternary ammonium salts of compounds having the desired cyanine heterocyclic nucleus in a suitable solvent, such as acetic anhydride and nitrobenzene, by heating. Other processes which may be used are taught in U.S. Pats. 3,431,111 and 3,632,808.

The alkyl substituted quaternary ammonium salts of compounds having the desired cyanine heterocyclic nucleus can be represented by the formula:

where, for example, A is methyl, substituted methyl, e.g., methoxymethyl, etc. A methine chain may be formed by joining the carbon atom of the methyl group of A and R₄. The other symbols have the same meaning as in Formula I.

Preferable dimethinecyanine dyes used in the present invention are represented by the following formula (I).

25 In the formula, R_1 represents a hydrogen atom or nitro group, R_2 represents a hydrogen atom, chlorine atom, lower (C_1-C_8) alkyl group, carboxyl group or lower (C_1-C_4) alkoxycarbonyl group, R_3 represents a hydrogen atom, alkyl group having 1-6 carbon atoms or aryl group such as phenyl or substituted phenyl such as tolyl, methoxyphenyl and nitrophenyl, R_4 represents an alkyl group having 1-6 carbon atoms, allyl group or aryl group such as phenyl or substituted phenyl, L_1 represents an unsubstituted methine group, L_2 represents methine group, e.g., a methine group which can be lower alkyl (C_1-C_8) substituted, aralkyl substituted, e.g., benzyl, aryl substituted, e.g., phenyl, etc., substituted, wherein a substituent in L_2 may bind to R_4 to form a methylene chain, m and n each represent 1 or 2, X^- represents an anion, and Z represent the non-metallic atoms necessary to complete a cyanine heterocyclic nucleus.

to complete a cyanine heterocyclic nucleus.

In formula (I), R_2 and Z were described in detail in the above. Examples of the alkyl group having 1-6 carbon atoms in R_3 include a methyl group, ethyl group, butyl group or hexyl group, which may be substituted, for example, with a carboxy group. As the aryl group in R_3 , a phenyl group and a tolyl group are particularly preferable. Examples of the alkyl group having 1-6 carbon atoms in R_4 , include, for example, a methyl group, ethyl group, propyl group, hexyl group, a hydroxyalkyl group (e.g., a β -hydroxyethyl group), alkoxyalkyl groups (e.g., a β -methoxyethyl group), carboxyalkyl groups (e.g., β -carboxypropyl group), sulfoalkyl groups (e.g., a γ -sulfo-propyl group) and aralkyl groups (e.g., a monocyclic aralkyl group, preferably, having less than 3 carbon atoms in the alkyl moiety such as a phenethyl group and a benzyl group). As examples of the aryl group in R_4 , a phenyl group and a tolyl group are particularly preferred. With respect to L_2 , the substituent in the substituted methine group may be, for example, a methyl group, ethyl group, carboxyethyl group, phenethyl group, hydroxyethyl group, a methoxyethyl group, and this substituent may bind to R_4 to form a methylene group. In this case, it is particularly preferred to form a 5- or 6-member ring.

As examples of X^- , there are, for example, a chlorine ion, bromine ion, iodine ion, *p*-toluenesulfonic acid ion, ethylsulfonic acid ion and a perchlorate ion. n is 1 in the case that the compound represented by the formula (I) has a betaine structure or 2 in the other cases.

In the following, particularly preferred examples of the compounds represented by the formula (I) are described, wherein the maximum absorption wave length in a methanol solution of the compound

TABLE—Continued

TABLE—Continued

16-----		$\lambda_{\text{max.}}^{\text{MeOH}}$ 432 nm.

In the following, examples of the synthesis of various sensitizers are described.

SYNTHESIS 1

2 - (2 - (1 - methyl - 2 - ethoxycarbonyl - 3 - indolyl) vinyl) - 1,3 - diethylimidazo(4,5 - b)quinoxalium - p - toluenesulfonate Dye (2)

1.0 g. of 1-methyl-2-ethoxycarbonyl-3-formylindole and 1.82 g. of 2-methyl-1,3-diethylimidazo(4,5-b)quinoxalium-p-toluenesulfonate were added to 20 ml. of acetic anhydride. After refluxing for 10 minutes by boiling, the solution was cooled with ice water whereby crystals precipitated. After adding about 200 ml. of ethyl alcohol thereto, the crystals were separated by filtration and washed with a solvent mixture of ethyl ether and acetone. The crystals were then recrystallized from a solvent mixture of ethanol and methanol. Thus, 1.6 g. (yield: 59 wt. percent based on starting materials; hereafter all dye yields are on the same basis) of Dye (2) (m.p.: 207° C.) was obtained.

SYNTHESIS 2

2-(2-(1-ethyl-2-chloro-3-indolyl)vinyl)-1-ethylbenzoxazolium iodide Dye (9)

2.1 g. of 2-methyl-1-ethylbenzoxazolium iodide and 1.5 g. of 1-ethyl-2-chloro-3-formylindole were added to 20 ml. of acetic anhydride. After refluxing for about 10 minutes by heating, the mixture was treated in the same manner as in Synthesis 1. By crystallizing from a solvent mixture

of ethanol and methanol, 1.2 g. (yield: 35%) of Dye (9) (m.p.: 230° C.) was obtained.

Other dimethinecyanine dyes can be synthesized in a manner similar to those described by merely substituting appropriate starting materials. The synthesis procedure per se is conventional.

It is further preferred that an organic desensitizer be included in the direct positive emulsions of the present invention.

The organic desensitizers used in the present invention are substances which have the ability to trap free electrons generated in silver halide particles by the application of radiant rays, and are substances which are adsorbed in the silver halide particles. Preferably, they are compounds having a maximum occupied electron energy level lower than that of the valence electron zone of the particles. Measurement of the values of the electron energy levels can be made, though complicated operations are necessary.

For example, determination for simple symmetric cyanine dyes is described in "Photographic Science and Engineering," Vol. 11(3), page 129 (1967), Tani and Kikuchi. Another such determination for typical merocyanine dyes is described in Preprint (No. B-12) of "International Congress of Photographic Science," 1970 (Moscow), Shiba and Kubodera.

It is known that the electron energy level corresponds primarily to an anode polarographic half-wave potential (E_{ox}) and a cathode polarographic half-wave potential (E_{red}). Many of such organic desensitizers are described

in, for example, U.S. Pats. 3,023,102, 3,314,796, 2,901,351 and 3,367,779, in British Pats. 723,019, 698,575, 698,576, 834,839, 667,206, 748,681, 796,873, 875,887, 905,237, 907,367 and 940,152, French Pats. 1,520,824, 1,518,094, 1,518,095, 1,520,819, 1,520,823, 1,520,821 and 1,523,626, Belgian Pats. 722,457 and 722,594, and Japanese Patent Publication No. Sho 43-13,167 and No. 43-14,500.

Any desensitizer described above can be used in the present invention. However desensitizers which give a particularly preferred result are compounds represented by formula (II) in which the cathode polarographic half-wave potential (E_{red}) is more positive than —1.0 volt.

In formula (II), R represents an alkyl group or allyl group, Z, X[⊖] and m each have the same meaning as in formula (I) and "a" represents 1 or 2.

Specific examples of R include a methyl group, ethyl group, butyl group, hydroxyalkyl groups (e.g., an hydroxyethyl group), carboxyalkyl groups (e.g., a carboxymethyl group and a 3-carboxylpropyl group) and sulfoalkyl groups (e.g., a 2-sulfoethyl group and a 4-sulfonybutyl group).

Other organic desensitizers used in the present invention with success include, for example,

phenosafranine,
pinakryptol yellow,
5-m-nitrobenzylidene rhodanine,
3-ethyl-5-m-nitrobenzylidene rhodanine,
3-ethyl-5-(2,4-dinitrobenzylidene)rhodanine,
5-o-nitrobenzylidene-3-phenyl rhodanine,
1',3-diethyl-6-nitrothia-2'-cyanine iodide,
4-nitro-6-chlorobenzotriazole,
3,3'-diethyl-6,6'-dinitro-9-phenyl-thiacarbocyanine iodide,
2-(p-dimethylaminophenyliminomethyl)benzothiazole
ethoethyl sulfate,
Crystal Violet,
3,3'-diethyl-6,6'-dinitro-thiacarbocyanine ethyl sulfate,
1',3-diethyl-6-nitrothia-2'-cyanine iodide,
1,3-diamino-5-methylphenazium chloride,
4-nitro-6-chlorobenzotriazole,
3,3'-di-p-nitrobenzylthiacarbocyanine bromide,
3,3'-di-p-nitrophenylthiacarbocyanine iodide,
3,3'-di-o-nitrophenylthiacarbocyanine perchlorate,
3,3'-dimethyl-9-trifluoromethylthiacarbocyanine iodide,
9-(2,4-dinitrophenylmercapto)-3,3'-diethylthiacar-
bocyanine iodide,
bis-(4,6-diphenylpyridyl-2-trimethine cyanine perchlorate,
anhydrous 2-p-dimethylaminophenyl-iminomethyl-6-nitro-
3-(4-sulfonybutyl)benzothiazolium hydroxide,
1-(2-benzothiazolyl)-2-(p-dimethylaminostyryl)-4,6-
diphenylpyridinium iodide,
1,3-diethyl-5-(1,3-neopentylene-6-(1,3,3-trimethyl-2-
indolinylidene)-2,4-hexadienylidene)-2-thiobarbituric
acid,
2,3,5-triphenyl-2H-tetrazolium chloride,
2-(4-iodophenyl)-3-(4-nitrophenyl)-5-phenyl-tetrazolium
chloride,
1-methyl-8-nitroquinolinium methyl sulfate, and
3,6-bis-(4-(3-ethyl-2-benzothiazolinylidene)-2-butene-
dene)-1,2,4,5-cyclohexanetetronate.

As examples of the silver halide emulsions used in the present invention, there are silver chloride, silver bromide, silver bromochloride, silver iodochloride and silver iodo-
bromochloride.

Though the silver halide may have a particle size in the range of those as are commonly used in this art, those having an average particle size of $0.05\text{ }\mu$ — $1.0\text{ }\mu$ give a particularly preferred result. The silver halide used in the present invention may be composed of either regular particles or irregular particles, but regular particles display a more preferred effect. (See U.S. Pat. 3,501,306.)

While either monodispersed emulsions or non-monodispersed emulsions may be used in the present invention, monodispersed emulsions are preferably used. (See U.S. Pat. 3,501,306.)

5 In general, raw emulsions used in direct positive silver halide photosensitive materials are classified into two types.

In one type the emulsion has nuclei for trapping free electrons in the interior of the silver halide crystals, the 10 surface of which has previously been chemically fogged. A characteristic of emulsions of this type is that they directly form positive images themselves, and it is possible only not to increase a spectral sensitization function but to sensitize the intrinsic absorption region of such emulsions by adding sensitizing dye(s) thereto. In emulsions of this type the compositions of the silver halides present should be adjusted so that chemical sensitizers or metal salts of a Group VIII metal which are used to give free electron trapping nuclei easily enter into the interior 15 of the silver halide.

Further, by addition of the organic desensitizer, it is 20 possible to decrease minimum density ("clean out") and particularly to prevent "re-reversal." Furthermore, it is possible to increase the maximum density, sensitization 25 and to improvement "clean-out" by adding bromine ions in an amount of from 1 to 10 mol percent or iodine ions in an amount of from 0.2 to 3 mol percent based on the silver halide.

The emulsion of this type is described in U.S. Pats. Nos. 30 2,401,051, 2,717,833, 2,976,149 and 3,023,102, British Pats. Nos. 707,704, 1,097,999 and 1,520,822, and French Nos. 1,523,626, 1,520,817 and 1,520,824.

The second type of raw emulsions used in forming 35 direct positives are those which do not have free electron trapping nuclei in the interior of the silver halide but wherein the surface is chemically fogged. These emulsions are silver halide emulsions composed of regular crystals which do not have a twinning plane and which are as free 40 of lattice defects as possible. Such emulsions are preferably pure silver bromide. These emulsions do not form direct positive images themselves. However, if they adsorb organic desensitizer in the silver halide of the emulsions, direct positive images are obtained at high sensitivity.

The emulsion of this type is described in U.S. Pats. Nos. 45 3,501,306, 3,501,307, 3,501,310 and 3,531,288, British Pats. Nos. 1,186,717, 1,186,714 and 1,186,716 and French Pats. Nos. 1,520,821, 1,520,817, 1,522,354 and 1,520,824.

In the present invention, either of the above raw emulsions can be used, i.e., both raw emulsions can be effectively sensitized by adding the compounds in accordance 50 with the present invention, preferably those represented by formula (I).

The silver halide emulsions used in the present invention can be fogged by light or chemically. Chemical fog 55 nuclei can be formed by adding, for example, hydrazine derivatives, formalin, thiourea dioxide, polyamine compounds, amine borane, methyl dichlorosilane and other known agents as disclosed in Belgian Pats. Nos. 721,564 and 708,563, U.S. Pat. No. 2,588,982, British Pat. No. 821,251, French Pat. No. 739,755 and Japanese Patent Publication No. 43-13,488.

Further, fog nuclei can be formed by using a reducer together with metal ions nobler than silver (for example, gold ions, platinum ions and iridium ions) or further with halogen ions, as disclosed in U.S. Pats. Nos. 2,717,833 and 3,023,102, Belgian Pats. Nos. 713,272 and 721,567 and British Pat. No. 707,704.

In the emulsions used in the present invention, gelatin is usually used as the protective colloid, and inactive 65 gelatin (inert gelatin) is preferably used. Instead of gelatin, however, photographically inactive gelatin derivatives and water soluble synthetic polymers (for example, polyvinyl acrylate, polyvinyl alcohol, polyvinyl pyrrolidone, polyvinyl alginate, carboxymethyl cellulose and hydroxymethyl cellulose) can be used, alone or as mixtures.

75 The direct positive silver halide emulsions used in the

present invention may contain additives such as a fog nuclei stabilizers (e.g. mercapto compounds, thione compounds and tetrazaindene compounds), an agent to decrease minimum density (e.g. stilbene compounds and triazine compounds), a whitening agent, an ultraviolet ray absorbing agent, a hardener (e.g. chromium alum, 2,4-dichloro-s-triazine compounds, azilydine compounds, epoxy compounds, mucohalogen acids and halogenoformyl-maleic acid derivatives), a coating assistant (e.g. sodium polyalkylene sulfonate, saponin and anionic surface active agents having a betaine structure), an anti-septic, a plasticizer (e.g. polyalkylacrylate, alkylacrylate-acrylic acid copolymers and polyalkylene oxide) and a color coupler.

The amount of the dimethine dyes used in the present invention depends upon largely on the quantity of silver halide and the surface area of the silver halide particles, but 1×10^{-6} to 2×10^{-2} mols per mole of silver salt provides good results.

These dyes are applied by dissolving them in water or water miscible solvents such as methanol, ethanol, ethylene glycol monomethyl ether, methyl ethyl ketone, acetone and pyridine. Ultraonic vibrations can be applied to the dyes during dissolution, if desired. Further, the methods used in the sensitization of negative type emulsions, for example, as described in Japanese Patent Publication No. Sho 44-23,389, Sho 44-27,555 and Sho 44-22,948, U.S. Pats. 3,485,634, 3,342,605 and 2,912,343, or German Pat. 1,947,935 can also be used. The addition of the dyes to the emulsion is conveniently carried out just before application to the support, but the dyes may be added during chemical ripening or at precipitation of the emulsion.

An amount of the organic desensitizer used in the present invention varies depending upon the kind thereof, but 2×10^{-7} – 10^{-1} mols per mol of the silver halide(s) is preferably used.

The emulsions according to the present invention can be applied to many kinds of supports to produce photographic elements. The emulsions may be applied to one surface or both surfaces of the support. The support may be transparent or opaque. As typical supports there are cellulose nitrate films, cellulose acetate films, polyvinyl acetal films, polystyrene films, polyethylene terephthalate films and other polyester films, glass, paper, metal, wood, etc. Plastic coated paper can also be used.

After exposure to light, the emulsions according to this invention are preferably treated in a development bath, a fixing bath and a stabilizing bath or in a bath which combines all of these treatments.

One characteristic of the present invention is to sensitize direct positive emulsions using certain new dimethine dyes which do not cause substantial residual color. A chemical structural feature of the new dimethine dyes is that the 2-position of the indole nucleus is substituted by a hydrogen atom, lower alkyl group, chlorine atom, carboxyl group or lower alkoxy carbonyl group.

It is described in U.S. Pat. 2,323,187 that sensitizing dyes which have a sensitizing function for common negative emulsions, particularly carbocyanine dyes, are effective for the sensitization of direct positive emulsions if they are used in a very large amount. However, this method is not preferred since the dyes strongly color the emulsions and cause residual color. On the other hand, it is described in British Pats. 970,621 and 1,186,714 that dimethine dyes having a 2-phenylindole nucleus or 2-pyridyl-indole nucleus show an excellent reversal property. However, they are unsatisfactory because residual color is caused. In the case of adding such dyes to direct positive emulsions until maximum sensitivity is obtained, a particular tendency for residual color to occur is encountered.

The dimethine dyes discovered by the present inventors have the characteristic that the residual color is very low, with residual color hardly being observed in the case that the 2-position of the indole nucleus is substituted by a carboxyl group or a lower alkoxycarbonyl group.

The second characteristic of the present invention is that the maximum density of the direct positive emulsion does not decrease substantially upon the use of the dyes of the present invention.

5 Not only carbocyanine dyes and merocyanine dyes
which are useful for sensitization of negative emulsions
but dimethine dyes having a 2-phenylindole nucleus some-
times cause deterioration of the maximum density of di-
rect positive emulsions. Decrease of the maximum density
10 is caused not only just after application of the direct positive
photographic emulsions but also during storage of
the emulsions. This deterioration of the direct positive
photosensitive materials with the lapse of time is larger
than that of common negative photosensitive materials.
15 Accordingly, the improvement of this point is an impor-
tant subject. The new dimethine dyes used in the present
invention have excellent properties in this respect.

The third characteristic of the present invention is that not only do the dimethine dyes used in the present invention cause a low degree of residual color but also flattening of the characteristic curve (softening) is small. In general, carbocyanine dyes and merocyanine dyes which are useful for the sensitization of negative emulsions have a tendency to flatten the characteristic curve. This flattening of the characteristic curve is not preferred in a high contrast direct positive sensitive materials such as reproduction films for lithotype films.

The direct positive silver halide emulsions sensitized by the dimethine dyes used in the present invention have a good clean-out (minimum density) and have the excellent characteristic that re-reversal does not substantially occur.

As mentioned above, the new dimethine dyes used in the present invention have many excellent characteristics. However, if these dyes are used together with the organic desensitizer, reversal sensitivity further increases and it is possible to produce direct positive silver halide emulsions having good clean-out.

The direct positive silver halide emulsions according to the present invention can be used not only for hard direct positive silver halide photosensitive materials such as photosensitive materials for the reproduction of lithotype films and photosensitive materials for copying originals, but also for comparatively soft direct positive silver halide sensitive materials such as photosensitive materials for the reproduction of microfilm and photosensitive materials for the reproduction of X-ray films, etc. Further, they can be used for color photosensitive materials.

The direct positive silver halide emulsions according to the present invention are useful not only in the case of application of light but also in the case of application of electrons X-rays and γ -rays, etc.

The present invention will now be illustrated in greater detail by several examples. In the examples, the dyes used for comparison purposes were as follows:

EXAMPLE 1

In order to prepare a raw emulsion, Solutions 1-4 were prepared according to the following formulations:

Solution 1:

35	Inactive gelatin	-----	g--	8
	Aqueous solution of potassium bromide (1 normal)	-----	cc--	5
	Water (60° C.)	-----	cc--	500

Solution 2:

40	Silver nitrate	-----	g--	100
	Water (60° C.)	-----	cc--	500

Solution 3:

	Potassium bromide	-----	g--	70
	Water (60° C.)	-----	cc--	150

Solution 4:

45	Inactive gelatin	-----	g--	75
	Water	-----	cc--	300

Solution 2 and Solution 3 were slowly added to Solution 1 over 50 minutes while keeping all solutions at 60° C. The mixture was then subjected to physical ripening at 60° C. for 5 minutes. Then, 15 cc. of a 0.2N solution of potassium iodide was added thereto and the pH was adjusted to 6.0 by adding silver nitrate solution thereto. After adjusting the pH to 10 with a sodium hydroxide solution, the solution was subjected to ripening for 10 minutes by adding 1.2 mg. hydrazine and 1.0 mg. of potassium tetrachloroaurate (III) thereto. The solution was then neutralized with citric acid and washed with water. Solution 4 was added thereto to prepare a raw emulsion. The resulting emulsion contained silver halide particles having an average particle size of about 0.2 μ comprised particles of a regular tetragonal system having a (100) phase.

To this raw emulsion, dyes were added in accordance with the formulations shown in Table 1 and 40 ml./kg. of emulsion of as 4 wt. percent aqueous solution of saponin was added. The resulting emulsions were applied to cellulose triacetate films so as to be about 5 μ in dry film thickness to thereby produce samples. Each sample was exposed for 1 second through a light wedge with a light source of 2854° K. (tungsten light). Then the samples were developed at 20° C. for 2 minutes using the following developer and fixed in an acid hardening fixer. By measurement of the density of the samples with a P-type densitometer produced by Fuji Photo Film

Co., Ltd., the characteristic curves of the samples were obtained. Results of measurement of the sensitivity, the maximum optical density ($D_{max.}$) and the minimum optical density ($D_{min.}$) of each sample are shown in Table 1.

In Table 1, the sensitivity is shown by the inverse number of the exposure necessary to give a concentration of

$$\frac{D_{max.} + D_{min.}}{2}$$

and is the value based on the sensitivity of each comparison dye being set at 100.

Composition of the developer:

	G.
Metol	3.1
Anhydrous sodium sulfite	45
Hydroquinone	12
Sodium carbonate monohydrate	79
Potassium bromide	2
Water to make 1 liter.	

This is used by diluting 1:1 with water.

TABLE 1

Sample number:	Dye (molar concentration) cc./100 g. of emulsion	Sensi- tivity	$D_{max.}$	$D_{min.}$
1.....(1)	(8×10 ⁻²)	16	138	3.2
.....(A)	(8×10 ⁻²)	16	100	2.6
2.....(2)	(8×10 ⁻²)	8	105	3.0
.....(B)	(8×10 ⁻²)	8	100	2.5
3.....(3)	(8×10 ⁻²)	8	123	3.1
.....(C)	(8×10 ⁻²)	8	100	2.8
4.....(6)	(8×10 ⁻²)	8	120	3.0
.....(F)	(8×10 ⁻²)	8	100	2.6
5.....(7)	(8×10 ⁻²)	32	416	3.2
.....(G)	(8×10 ⁻²)	32	100	2.5
6.....(10)	(8×10 ⁻²)	32	110	2.9
.....(J)	(8×10 ⁻²)	32	100	2.2
				0.04

It will be understood from Table 1 that the dyes of the present invention have excellent characteristics in that $D_{max.}$ is high, the clean-out is good and the sensitivity is high as compared with the comparison dyes.

EXAMPLE 2

First, a raw emulsion was prepared as follows.

To Solution 1 (prepared by dissolving 10 g. of inactive gelatin in 5 cc. of a 1N sodium chloride solution and 500 cc. of water at 60° C.), Solution 2 (prepared by dissolving 100 g. of silver nitrate in 500 cc. of water at 60° C.) and Solution 3 (prepared by dissolving 35 g. of sodium chloride in 300 cc. of water at 60° C.) were added over 20 minutes while stirring at 60° C. After addition, the mixture was subjected to ripening for 5 minutes at 60° C. Then, Solution 4 (prepared by dissolving 14 g. of potassium bromide in 200 cc. of water at 60° C.) was added over 5 minutes with stirring. After ripening for 10 minutes at 60° C., the temperature was reduced to 35° C. and the product was washed with water. It was then dissolved by warming, and the pH was adjusted to 10. After adding hydrazine and the gold chloride in the amounts given in Example 1, the mixture was subjected to ripening for 10 minutes. Then the pH was adjusted to 6.5 with 8 ml. of 10 wt. percent citric acid. Furthermore, Solution 5 (prepared by dissolving 75 g. of inert gelatin in 300 cc. of water) was added thereto to produce a raw emulsion. The average particle size of silver halide particles in the resulting raw emulsion was about 0.15 μ .

To this raw emulsion, 32 cc. of a methanol solution of pinnacryptol yellow (5×10^{-2} moles present) was added. Then dyes were added in accordance with Table 2. After adding mucochloric acid and saponin (as in Example 1), the emulsions were applied to cellulose triacetate films so as to have dry film thickness of about 2 μ to thereby produce samples.

Each sample was exposed to light for 1 second through a light wedge using a 2854° K. tungsten light as the light source, developed for 3 minutes at 20° C. using the developer having the following formulation and fixed with an acid hardening fixer.

5	Developer:	
	Water (about 30° C.)	cc. 50
	Anhydrous sodium sulfite	g. 30
	Paraformaldehyde	g. 7.5
10	Sodium bisulfate	g. 2.2
	Boric acid	g. 7.5
	Hydroquinone	g. 22.5
	Potassium bromide	g. 1.6
	Water to make 1 liter.	

By density determinations using a P-type desitometer produced by Fuji Photo Film Co., Ltd., characteristic curves of the samples were obtained. In the same manner as in Example 1, the sensitivity, $D_{max.}$ and $D_{min.}$ were determined. The density of the residual color was also determined, the density of residual color being shown as the optical density as determined by the above-described densitometer using a blue filter after dipping the emulsion coated samples immediately in an acid hardening fixer at 20° C. for a minute and 30 seconds without exposure to light, and rinsing for 3 minutes. The results are shown in Table 2.

TABLE 2

30	Dye (molar concen- tration) cc./100 g. of emulsion	Sensi- tivity	$D_{max.}$	$D_{min.}$	Resid- ual color
Sample No:					
7.....(4)	(2.5×10 ⁻²)	8	467	3.2	0.06
.....(D)	(2.5×10 ⁻²)	8	100	3.0	0.07
8.....(5)	(2.5×10 ⁻²)	16	155	2.5	0.04
.....(E)	(2.5×10 ⁻²)	16	100	2.4	0.04
9.....(8)	(2.5×10 ⁻²)	8	107	2.9	0.04
.....(H)	(2.5×10 ⁻²)	8	100	2.5	0.04
10.....(9)	(2.5×10 ⁻²)	8	104	2.7	0.04
.....(I)	(2.5×10 ⁻²)	8	100	2.6	0.04
11.....(13)	(2.5×10 ⁻²)	32	118	2.9	0.04
.....(K)	(2.5×10 ⁻²)	32	100	2.6	0.04
12.....(21)	(2.5×10 ⁻²)	16	152	3.0	0.04
.....(L)	(2.5×10 ⁻²)	16	100	2.8	0.04

45 As is clear from this table, the dyes, of the present invention have excellent properties with respect to sensitivity, maximum optical density and cleanout, and the residual color is low. It is surprising that this difference is based on the difference of the substituent in the 2-position of the indolene nucleus.

EXAMPLE 3

First, a raw emulsion was prepared as follows.

55 To Solution 1 (prepared by dissolving 10 g. of inactive gelatin in 5 cc. of 1N sodium chloride solution and 500 cc. of water at 60° C.), Solution 2 (prepared by dissolving 100 g. of silver nitrate in 500 cc. of water at 60° C.) and Solution 3 (prepared by dissolving 35 g. of sodium chloride and 14 g. of potassium bromide in 300 cc. of water at 60° C.) were added over 20 minutes while stirring at 60° C. After addition, the mixture was subjected to ripening for 5 minutes as in Example 2, and the temperature was reduced to 35° C. After washing with water, the mixture was dissolved again by warming and the pH was adjusted to 10. After adding hydrazine and gold chloride as in Example 2, the mixture was subjected to ripening for 10 minutes at 60° C. and the pH was adjusted to 6.5 with citric acid as in Example 2.

60 Furthermore, Solution 5 (prepared by dissolving 75 g. of inactive gelatin in 300 cc. of water) was added thereto to produce a raw emulsion. The average particle size of silver halide particles in the raw emulsion was about 0.15 μ .

65 To this raw emulsion, 32 cc. of a methanol solution of pinnacryptol yellow (5×10^{-2} moles present) was added. Then dyes were added in accordance with Table 2. After adding mucochloric acid and saponin (as in Example 1), the emulsions were applied to cellulose triacetate films so as to have dry film thickness of about 2 μ to thereby produce samples.

70 Furthermore, Solution 5 (prepared by dissolving 75 g. of inactive gelatin in 300 cc. of water) was added thereto to produce a raw emulsion. The average particle size of the silver halide particles in the raw emulsion was about 0.15 μ .

75 To this raw emulsion, 32 cc. of a methanol solution of pinnacryptol yellow (5×10^{-2} moles present) was added.

Then, dyes were added in accordance with Table 3. After adding mucochloric acid and saponin (as in Example 2), the emulsions were applied to cellulose triacetate films so as to have dry film thickness of about 2μ thereby produce two strips. One of the strips was preserved at 35°C . and 75% relative humidity for 30 days and exposed to light in the same manner as in Example 1. The other strip was exposed to light just after application and drying. These samples were developed, fixed and rinsed with water. The density of the resulting strips was determined with a P-type densitometer produced by Fuji Photo Film Co., Ltd. The results are shown in Table 3.

TABLE 3

Sample number:	(Dye (molar concentration) cc./100 g. of emulsion		Maximum optical density ($D_{\text{max.}}$)	
			Just after application	After preservation
12.....	(2)	(2.5×10^{-2})	8	3.0
	(B)	(2.5×10^{-2})	8	2.6
13.....	(9)	(2.5×10^{-2})	16	2.9
	(I)	(2.5×10^{-2})	16	2.4

As is clear from Table 3, the lowering of the maximum optical density ($D_{\text{max.}}$) with the passage of time is small for the dyes of the present invention as compared with the comparison dyes.

The most preferred embodiments of the present invention can be described as follows.

(1) Where the dimethine cyanine dyes are compounds represented by formula (I).

(2) Where the R_2 group of the dimethinecyanine dyes represented by formula (I) is a hydrogen atom, chlorine atom, carboxyl group or lower alkoxy carbonyl group.

(3) Where the organic desensitizer is a compound represented by formula (II):

wherein R represents an alkyl group, $X^\ominus$ represents an anion, m and a each represent 1 or 2, and Z represents the non-metallic atoms necessary to complete a 5- or 6-membered heterocyclic ring.

While the invention has been described in detail and with reference to specific embodiments thereof, it will be apparent to one skilled in the art that various changes and modifications can be made therein without departing from the spirit and scope thereof.

What is claimed is:

1. Fogged direct positive silver halide emulsions which contain at least one dimethinecyanine dye in which the 3-position of the indole nucleus, having a hydrogen atom, chlorine atom, lower alkyl group, carboxyl group or lower alkoxy carbonyl group in the 2-position thereof, joins to the 1-, 2-, 3-, or 4-position of the cyanine heterocyclic nucleus through a dimethine chain, with the proviso that only when the cyanine nucleus is isoquinoline is the joining to the 1- or 3-position, and when joining is to the 4-position, the cyanine nucleus comprises a quinoline or pyridine ring, said dimethinecyanine dye being present in an amount effective to provide maximum retained image density without residual color.

2. The direct positive emulsions of Claim 1 wherein the cyanine nucleus is selected from the group consisting of an oxazoline nucleus, oxazole nucleus, benzoxazole nucleus, naphthoxazole nucleus, thiazoline nucleus, thiazole nucleus, benzothiazole nucleus, naphthothiazole nucleus, selenazole nucleus, benzoselenazole nucleus, naphthoselenazole nucleus, 2-pyridine nucleus, 4-pyridine nucleus, 2-quinoline nucleus, 4-quinoline nucleus, 3-isoquinoline nucleus, 1-isoquinoline nucleus, benzimidazole nucleus, 3,3-dialkylindolenine nucleus, imidazo(4,5-b)quinoxaline nucleus and pyrrolidine nucleus.

3. The direct positive emulsions of Claim 2 wherein the cyanine nucleus is substituted with one or more members

selected from the group consisting of an alkyl group, an aryl group, a hydroxyl group, an alkoxy group, a carboxyl group, an alkoxy carbonyl group, a nitro group or a halogen atom.

4. The direct positive emulsions of Claim 1 wherein said dimethinecyanine dyes are represented by the formula:

wherein R_1 is a hydrogen atom or nitro group, R_2 is a hydrogen atom, C_1-C_8 alkyl group, carboxyl group or C_1-C_4 alkoxy carbonyl group, R_3 is a hydrogen atom or C_1-C_6 alkyl group, R_4 comprises a C_1-C_6 alkyl group, an allyl group or an aryl group, L_1 and L_2 comprise a methine group, m and n are 1 or 2, $X^\ominus$ is an anion, and Z represents the non-metallic atoms necessary to complete a cyanine heterocyclic nucleus.

5. The direct positive emulsions of Claim 4 wherein L_2 is a substituted methine group, wherein the substituent is selected from the group consisting of alkyl, alkoxyalkyl aralkyl or aryl.

6. The direct positive emulsions of Claim 4 wherein R_3 is phenyl or tolyl, R_4 is hydroxyalkyl, alkoxyalkyl, carboxyalkyl, sulfoalkyl or aralkyl with 1 to 6 carbon atoms in the alkyl chain, and R_4 is phenyl or tolyl.

7. The direct positive emulsions of Claim 1 which further include an organic desensitizer, which organic desensitizer has a cathodic polarographic half-wave potential (Ered) more positive than -1.0 .

8. The direct positive emulsions of Claim 7 wherein said organic desensitizer has a cathodic polarographic half-wave potential (Ered) more positive than -1.0 and has the formula:

wherein R is an alkyl group or allyl group, $X^\ominus$ is an anion, m and a are 1 or 2 and Z represents the non-metallic atoms necessary to complete a cyanine heterocyclic nucleus.

9. The direct positive emulsions of Claim 7 wherein from 2×10^{-7} to 10^{-1} moles of organic desensitizer is present per mole of silver halide present.

10. The direct positive emulsions of Claim 8 wherein R is an alkyl group and Z represents the non-metallic atoms necessary to complete a 5- or 6-membered heterocyclic ring.

11. The direct positive emulsions of Claim 1 wherein from 1×10^{-6} to 2×10^{-2} moles of dimethine dye per mole of silver halide is present.

12. The direct positive emulsions of Claim 1 wherein the 2-position of said indole nucleus is substituted with a hydrogen atom.

13. The direct positive emulsions of Claim 1 wherein the 2-position of said indole nucleus is substituted with a chlorine atom.

14. The direct positive emulsions of Claim 1 wherein the 2-position of said indole nucleus is substituted with a lower alkyl group.

15. The indirect positive emulsions of Claim 14 wherein said lower alkyl group has from 1 to 8 carbon atoms.

16. The direct positive emulsions of Claim 1 wherein the 2-position of said indole nucleus is substituted with a carboxyl group.

17. The direct positive emulsions of Claim 1 wherein the 2-position of said indole nucleus is substituted with a lower alkoxy carbonyl group.

21

18. The direct positive emulsions of Claim 17 wherein said lower alkoxy carbonyl group has from 1 to 4 carbon atoms.

22

19. The direct positive emulsions of Claim 4 wherein said dimethine cyanine dye is selected from the group consisting of:

23
